UNITED STATES PATENT OFFICE.

MORRIS J. STONE, OF ST. LOUIS, MISSOURI, ASSIGNOR TO STONE MANUFACTURING COMPANY, OF ST. LOUIS, MISSOURI, A CORPORATION OF MISSOURI.

DESIGN FOR A PHONOGRAPH-CABINET.

57,389.

Specification for Design.

Patented Mar. 15, 1921.

Application filed October 25, 1920. Serial No. 419,536. Term of patent 3½ years.

To all whom it may concern:

Be it known that I, MORRIS J. STONE, a citizen of the United States, residing at the city of St. Louis, State of Missouri, have invented a certain new, original, and ornamental Design for a Phonograph-Cabinet, of which the following is a specification, reference being had to the accompanying drawing, forming a part thereof.

In the drawing,

Figure 1 is a front elevation of a phonograph cabinet, showing my new design; and Fig. 2 is a side elevation thereof.

I claim:

The ornamental design for a phonograph cabinet substantially as shown.

MORRIS J. STONE.
